UNITED STATES PATENT OFFICE.

GEORGE C. BUCH, OF EUREKA, MISSOURI.

BOOT OR SHOE.

SPECIFICATION forming part of Letters Patent No. 291,490, dated January 8, 1884.

Application filed August 28, 1883. (No model.)

To all whom it may concern:

Be it known that I, GEORGE C. BUCH, of Eureka, St. Louis county, Missouri, have made a new and useful Improvement in Boots and Shoes, of which the following is a full, clear, and exact description, reference being had to the annexed drawings, making part of this specification, in which—

Figure 1 is a view in perspective of a boot or shoe, inverted, in which the present improvements are shown; Fig. 2, a view in perspective of the heel, a portion being broken away; Fig. 3, a view in perspective of the shank-piece; Fig. 4, a view in perspective similar to that of Fig. 1, the heel and a portion of the sole being removed to exhibit the springs; and Fig. 5, a cross-section taken through the sole in the plane indicated by dotted lines $\alpha\alpha$ on Fig. 4.

20 The same letters of reference denote the same parts.

The design of this improvement is to provide an elastic support.

A represents a boot or shoe, in which the present improvement is embodied. Except as modified by the improvement, the boot or shoe is of any of the ordinary types. In place, however, of a solid heel and sole, a system of springs is introduced into the heel, and also 30 into the sole beneath where the ball of the foot presses, and the heel and sole beneath the springs yield as the springs are compressed in use.

B represents the heel-spring, and C the sole-spring. Each of these springs, in practice, is 35 preferably sectional, as shown. The heel-spring B is made in sections $b b b$, and the sole-spring is composed of the sections $c c c$, any desired number of the sections in the heel 40 and also in the sole being employed. The sections $b b$ of the heel-spring are preferably arranged longitudinally in the boot or shoe, and they are made fast to the shoe, and preferably at one (the forward) end, b' , only. The springs $b b$ are suitably shaped to provide an elastic 45 bearing between the sole a and the heel D, being preferably elliptical as far as general outline is concerned. The heel D is provided with a flange, d , which is adapted to fit within 50 a flange, a' , which extends downward from the counter a^2 . The heel-flange d is provided with

the projections d' , which, when the heel is in place, engage in vertical elongated openings a^3 in the counter-flange. This serves to connect the heel with the main portion of the 55 shoe, but in such a manner as to allow of the heel being moved as the springs yield and expand in use. To give a finish to this part of the construction, the shank-piece E is attached to the shoe in front of the heel, and the counter-flange is provided with covering-strips a^4 . To leave the heel free to move, the shank-piece simply laps upon the forward end of the heel, but is not fastened thereto, and the strips a^4 at their lower ends are also preferably left free, 65 so as not to cramp the movement of the projections d' in the slots a^3 . The heel-flange d is preferably of metal, and the heel is fastened thereto; but, if desired, the heel and heel-flange may be in one piece. The sections $c c$ 70 of the spring C are arranged crosswise in the sole of the shoe; but they are preferably united in the direction of the length of the shoe and by means of a flexible strip or strips, c' , which strips extend longitudinally in it, serving both 75 to connect the sections $c c$, as by means of the rivets c^2 , and also to connect the entire system, C, of springs to the sole of the shoe, to which end the strips c' at one end thereof—say the inner end—are fastened to the upper sole, a^5 , 80 of the shoe—that is, the system, C, of springs is virtually inclosed in a space, which is provided between the upper sole, a^5 , and the outer sole, a .

When the springs $c c$ are compressed in use, 85 the two soles $a a^5$ are moved nearer together. The effect is to provide an elastic strip for the wearer, which, when the boot or shoe is finished, is entirely inclosed from view, so that the boot or shoe, in its external appearance, 90 closely resembles the ordinary article.

I claim—

1. The combination of the heel-piece D, the flange d , having projections d' , the flange a' , attached to the heel, and having elongated 95 openings, which receive said projections, and a heel-spring, substantially as described.

2. A boot or shoe having longitudinally-arranged springs for the heel and shank, in combination with a yielding heel-piece, D, 100 substantially as described.

3. A boot or shoe, having a transversely-

arranged sole-spring, C, consisting of sections c c c between the inner sole, a⁵, and the outer sole, a, substantially as described.

4. The combined heel and shank-spring B, 5 consisting of sections b b b, as a new article of manufacture, substantially as described.

5. The combination, with a hollow boot or shoe heel, of a spring, B, which is partially inclosed in the yielding heel and extended 10 forward thereof beneath the shank, thereby serving the double purpose of a heel-spring and a shank-spring, substantially as described.

6. The combination of the longitudinal

springs b b', curved as described, with a hollow yielding heel and a covering shank-piece, 15 E, substantially as described.

7. In a boot or shoe, the combination of the yielding heel D, the longitudinal heel and shank-spring B, the covering E for the forward portion of spring B, and the transverse 20 sole-springs C, all as described.

Witness my hand this 21st August, 1883.

G. C. BUCH.
